UNITED STATES PATENT OFFICE.

CHARLES HOMER HALL, OF CHICAGO, ILLINOIS.

HEEL.

1,415,442.

Specification of Letters Patent.

Patented May 9, 1922.

Application filed January 10, 1919. Serial No. 270,518.

To all whom it may concern:

Be it known that I, CHARLES H. HALL, a citizen of the United States, residing at Chicago, in the county of Cook and State of Illinois, have invented a new and useful Heel, of which the following is a specification.

The device forming the subject matter of this application is an article of footwear, 10 and one object of the invention is to provide a simple but efficient means whereby the advantages of a metal heel and a leather or rubber heel may be combined in a single structure.

Another object of the invention is to provide novel means for attaching the heel securely to the body portion of the shoe.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention 30 shown can be made without departing from the spirit of the invention.

In the accompanying drawings:—

Figure 1 shows in side elevation, a portion of a shoe constructed in accordance 35 with the invention; Figure 2 is a vertical section taken through the heel; Figure 3 is a top plan of the heel; and Figure 4 is a bottom plan of the heel.

The numeral 1 marks a shoe of any desired kind, having a sole 2 and an insole 3. A heel 4, preferably made of metal, abuts against the sole 2 and is provided in its upper surface with threaded openings 5. In its upper end, the heel 4 is supplied with a cavity 6, disposed adjacent to the forward edge of the heel. In the heel 4, at the base of the cavity 6, there is a threaded opening 7. A metal plate 8 is located between the sole 2 and the insole 3, above the heel 4. Screws 50 9, which preferably, are machine screws, are engaged with the plate 8 and pass downwardly through the sole 2, the said screws being engaged in the openings 5 of the heel 4. The numeral 10 marks a machine screw 55 engaged at its upper end with the plate 8 and passed downwardly through the sole 2,

the screw 10 traversing the cavity 6 and being threaded at its lower end into the opening 7 of the heel. A tread 11, made of rubber, leather, or any other suitable substance 60 is applied to the lower end of the heel 4 and is held in place by securing members, such as machine screws 12.

The construction of the device is such that the heel 4 may be assembled readily with a shoe and, with equal facility, be detached therefrom, it being possible to shift the heel from shoe to shoe. Further, when the tread 11 becomes worn, the tread may be detached readily, and be replaced by a new tread. It 70 is to be observed that the screw 10 passes down through the cavity 6. Consequently, by threading the screw 10 downwardly, the sole 2 and the plate 8 may be distorted slightly, so as to enter the upper end of the cavity 6, to some extent, thereby affording a secure connection between the heel 4 and the sole 2 of the shoe. It is to be observed that the plate 8 is secured at its rear end only, by means of the screws 9 to the heel 4, the forward end of the plate 8 being free. Consequently, when the screw 10 is threaded downwardly, the sole 2 may be distorted slightly so as to fit into the upper end of the cavity 6, as aforesaid, to bring about an unusually 85 secure connection between the heel and the body portion of the shoe.

Since the heel 4 is provided with the cavity 6, the heel, although made of metal, will be light in weight, it being possible to fashion the heel out of aluminum if desired. The heel 4 may be shifted from shoe to shoe, and may be enameled or colored otherwise, to match the color of the shoe. It is a well known fact that, frequently, a pair of shoes 95 will be rejected, simply because the heel is not satisfactory, the shoe, otherwise, being a perfect fit. In such an instance, if the heel forming the subject matter of this application is employed, a heel which is too high 100 or too low, may be replaced by a heel of proper height, the heel, of course, being made in all necessary sizes and shaped to suit the trade. If the tread 11 becomes 105 worn, it may be replaced readily, without detaching the heel 4 from the shoe.

Especial attention is directed to the fact that the present application provides a means whereby a rubber lift may be applied to a French heel. It is a well known fact, 110 that the application of a rubber lift to a French heel is a matter fraught with much

difficulty and that, although many methods have been proposed for attaching a rubber lift to a French heel, efforts in the past, along this line, have proved unsatisfactory. 5 When the device is constructed as shown in this application, the lift may be held on a French heel as securely as such a lift is held on a heel of any other kind.

Having thus described the invention, what 10 is claimed is:—

In a shoe, an upper and a heel, a sole superposed on the heel, a plate superposed on the sole, and a screw passing through the plate and the sole and threaded into the heel, 15 the screw having a head engaging the plate, the forward end of the plate being free, whereby the plate will move toward the heel and conform readily to the sole when the screw is advanced, and means for securing 20 the rear end of the plate fixedly to the heel,

against movement, whereby the plate will be prevented from moving longitudinally or laterally and leaving a space between the edge of the plate and the upper, the heel having a cavity through which the screw passes, 25 the cavity being located beneath the free portion of the plate, and beneath the corresponding portion of the sole, and being of sufficient size so as to permit the sole to yield slightly, thereby to secure a firm bearing engagement between the plate and the sole, regardless of minor irregularities in the sole or the plate. 30

In testimony that I claim the foregoing as my own, I have hereto affixed my signature 35 in the presence of two witnesses.

CHARLES HOMER HALL.
